COMBINED SCRUB PAIL AND MOP SQUEEZER

David B. Oas, S. Creek Road, R.D. 1,
Girard, Pa. 16417

Filed July 13, 1970, Ser. No. 23,910

Term of patent 14 years

Int. Cl. D7—05

U.S. Cl. D49—29

FIG. 2

FIG. 1

FIG. 3

FIG. 4

FIG. 5

FIG. 1 is a top perspective view of a combined scrub pail and mop squeezer showing my new design;

FIG. 2 is a vertical sectional view taken on the line 2—2 of FIG. 1;

FIG. 3 is a side elevational view;

FIG. 4 is an elevational view looking from the left of FIG. 3; and

FIG. 5 is an elevational view looking from the right of FIG. 3.

I claim:

The ornamental design for a combined scrub pail and mop squeezer, as shown.
